COMBINATION FLUORESCENT AND INCANDESCENT LANTERN

Darrell J. Lowrance, Tulsa, Okla., assignor to Lowrance Electronics, Inc., Tulsa, Okla.

Filed Sept. 7, 1972, Ser. No. 286,859

Term of patent 14 years

Int. Cl. D26—02

U.S. Cl. D48—24 R

FIG. 1 is a front view of the combined fluorescent and incandescent lantern, showing my new design.

FIG. 2 is an elevation view of one side thereof.

FIG. 3 is a rear elevational view thereof.

FIG. 4 is an elevation view of the other side thereof.

FIG. 5 is a top view thereof.

FIG. 6 is a bottom view thereof.

I claim:

The ornamental design for a combined fluorescent and incandescent lantern, substantially as shown and described.
